(57) **CLAIM**

The ornamental design for a control for a massage chair, as shown and described.

DESCRIPTION

FIG. 1 is a front view of a control for a massage chair according to the present invention.

FIG. 2 is a back view of the control of FIG. 1.

FIG. 3 is a top view of the control of FIG. 1.

FIG. 4 is a left side view of the control of FIG. 1. The right side view is a mirror image of the left side view in this configuration.

FIG. 5 is a left side view of the control of FIG. 1, shown in a pushed forward position.

FIG. 6 is a left side view of the control of FIG. 1, shown in a pulled up position.

FIG. 7 is a perspective view of the control of FIG. 1.

FIG. 8 is a front view of the control of FIG. 1, shown mounted for use in a massage chair environment.

FIG. 9 is a back view of the control of FIG. 1, shown mounted for use in a massage chair environment.

FIG. 10 is a top view of the control of FIG. 1, shown mounted for use in a massage chair environment.

FIG. 11 is a bottom view of the control of FIG. 1, shown mounted for use in a massage chair environment.

FIG. 12 is a left side view of the control of FIG. 1, shown mounted for use in a massage chair environment.

FIG. 13 is a right side view of the control of FIG. 1, shown mounted for use in a massage chair environment; and,

FIG. 14 is a perspective view of the control of FIG. 1, shown mounted for use in a massage chair environment.

The special dot-dot-dash broken line in FIG. 7 defines the bounds of the claimed design whereas the plain broken line showing of environmental detail in FIG. 7 is included for illustrative purposes only. All broken lines form no part of the claimed design.
